UNITED STATES PATENT OFFICE

LAWRENCE C. SALZER, OF AUBURN, NEW YORK

BLOWTORCH

Application filed August 15, 1930. Serial No. 475,500.

This invention appertains to blow torches and has for its object the provision of an article which is simple in construction, easy of manipulation, particularly in close quarters such as corners and angles, and which involves few parts.

While the drawings illustrate a preferred embodiment of the invention, it is to be understood that in adapting the means to meet specific needs and requirements, the design may be varied and changes in the minor details of construction may be resorted to within the scope of the invention as claimed, without departing from the spirit thereof.

For a full understanding of the invention and the merits thereof, reference is to be had to the following description and the drawings hereto attached, in which:

Figure 1 is a perspective view illustrative 20 of a blow torch embodying the invention.

Figure 2 is an enlarged detail sectional view, parts being broken away.

Corresponding and like parts are referred to in the following description and designated in the several views of the drawings by like reference characters.

The numeral 1 designates a burner pipe to which is fitted a nozzle 2. The pipe 1 may be of any length and size and has a handle 3 more or less tightly but slidably mounted thereon to prevent burning the hand. Fixed to the pipe 1 at its lower end, as seen in Figure 2, is a tapered collar 3'. A small metal tube 4 extends through the pipe 1 and nozzle 2 and is centrally disposed within the nozzle and terminates a short distance from the extremity thereof. The device includes a Y-fitting which comprises a ball 5 and coupling ends 6, 7 and 8. The coupling ends 7 and 8 are juxtaposed and are outwardly diverged from the ball 5. The coupling end 6 is disposed opposite the coupling ends 7 and 8. A small metal tube 9 extends through the ball 5 and coupling ends 6 and 8. A plug 10 closes the outer end of the element 8 and the tube 9 extends therethrough. A flexible tube 11 connects the coupling end 7 with an outlet 12 which is controlled by a suitable valve. A flexible tube 13 connects the coupling end 8 50 with an outlet 14 which likewise consists of

a suitable valve. A flexible tube 15 connects the coupling end 6 with the end of the burner pipe 1 remote from the nozzle 2, said tube having its end portion clamped between the flat surface of the collar 3' and the flat lower end face of the handle 3. The tube 15 may be of any length, eight to ten feet, more or less, to admit of the torch covering a large area. A small flexible tube 16 is disposed within the tube 15 and connects the tube 9 55 with the tube 4. The tubes 11, 13, 15 and 16 are usually of rubber. The tubes 4 and 9 are of metal.

The branch tubes 11 and 13 are short and make provision for connecting the main or extension tube 15 to the air and gas outlets. The outlet 12 is connected to a suitable source of gas supply whereas the outlet 14 is connected with a suitable source of compressed air. When the torch is connected to the air and gas outlets, the flame may be regulated by adjusting the valves associated with the respective outlets, as will be readily understood. The gas from the valve controlled outlet 12 passes through the branch tube 11, Y-fitting, main tube 15, burner pipe 1, and nozzle 2 and is consumed as it issues from the nozzle. The compressed air from the outlet 14 passes through the branch tube 13 and tubes 9, 16 and 4, and issues from the tube 4 adjacent the extremity of the nozzle and discharges into the flame in a jet, thereby promoting combustion of the gas and intensifying the flame which may be regulated to suit the work by adjusting the valves 12 and 14 in a manner readily understood. It is observed that there is but a single line of tubing 15 and a single burner pipe 1, and, in consequence, there is no liability of two lines becoming entangled or inconvenience being experienced by the provision of a number of burner pipes.

Attention is directed to the fact that the tubing 15 may be removed from the pipe 1 inasmuch as the handle 3 may be shifted forwardly for freeing the end portion of said tubing from between the flat end face of the handle and the collar 3'. However, under normal conditions, the end of the hose will be firmly held between the handle and said

collar so that accidental detachment of the hose will be prevented.

What is claimed is:

- A blow torch including a burner pipe having a nozzle, a collar carried at one end of the burner pipe, a handle mounted on said burner pipe, a small rigid air tube within the burner pipe and nozzle, a Y-fitting comprising a ball and coupling ends, a small rigid tube passing through the ball and one of the coupling ends of the Y-fitting, a flexible tube connecting the burner pipe with the Y-fitting and having its end portion normally clamped between the collar and handle, said handle being slidable for releasing said end portion of the flexible tube whereby said flexible tube may be disconnected, a small flexible tube within the first mentioned flexible tube and connecting the small rigid air tube with the small rigid tube in the Y-fitting, and branch tubes forming connecting means between the Y-fitting and valve controlled gas and compressed air outlets.

In testimony whereof I affix my signature.
